UNITED STATES PATENT OFFICE.

WILLIAM W. ROSENFIELD, OF NEW YORK, N. Y.

ROTARY FAN.

1,233,707.

Specification of Letters Patent. Patented July 17, 1917.

Application filed July 1, 1912. Serial No. 706,843.

To all whom it may concern:

Be it known that I, WILLIAM W. ROSENFIELD, a citizen of the United States, residing at New York city, county of New York, 5 and State of New York, have invented certain new and useful Improvements in Rotary Fans, fully described and represented in the following specification and the accompanying drawings, forming a part of the same.

This invention relates to rotary centrifugal fans, and the object of the invention is to improve the construction of such fans, and especially to provide a fan which shall 15 be light in weight, strong and rigid, and of inexpensive construction, and shall have other advantages hereinafter referred to. The invention has been made especially with the idea of providing a fan suitable for use 20 in suction cleaners of the self-contained type in which the motor, fan, suction nozzle and dirt receptacle are mounted to move together as the suction or cleaning nozzle is moved over the surface to be cleaned, 25 and in which light weight combined with strength and durability are essential. It is to be understood, however, that fans embodying the present invention may be applied to any and all other uses for which it 30 is found suitable.

A full understanding of the invention can best be given by a detailed description of a construction embodying the same in an approved form, and such a description will 35 now be given in connection with the accompanying drawings; in which.

Figure 1 is a longitudinal sectional view of a self-contained suction cleaner provided with a rotary fan made in accordance with 40 the invention;

Fig. 2 is a view of the fan removed from its shaft; and

Fig. 3 is a sectional view of the fan taken on line 3—3 of Fig. 2.

Referring to the drawings, and first to Fig. 1, 10 represents a rotary suction fan mounted to rotate about a horizontal axis in a fan casing 11, the fan being mounted on and driven by the shaft 12 of an electric 50 motor 13 which is mounted in a supporting casing 14 extending rearwardly from the fan casing. The front wall of the fan casing is formed with a central opening and has secured to it a downwardly extending 55 casing 15 providing an intake passage and

the lower end of which is shaped to form a suction or cleaning nozzle 16 which rests on the floor when the cleaner is in use. A discharge passage 17 leads off tangentially from the bottom of the fan chamber and 60 communicates through a backwardly leading pipe 18 with a porous receptacle 19 for receiving the dirt and dust discharged from the fan chamber. The receptacle 19 is hung from an operating handle rod 20 which is 65 pivotally connected to the rear end of the motor case to swing vertically and by which the suction cleaner is moved over the floor or surface to be cleaned. A pair of running wheels 21, of which one is shown in the 70 drawings, serve with the nozzle 16 to support the cleaner. The suction cleaner aside from the fan itself forms no part of the present invention but is shown for the purpose of showing the use of the fan in an apparatus to which it is particularly adapted.

Referring now to the fan itself the outwardly extending blades of the fan are formed by strips of sheet metal each of which strips is bent to form two diverging 80 fan blades *a* and *b* respectively, and the intermediate or bent portion of each strip is secured to a central part or hub 25, which as shown is of cylindrical form bored to receive the shaft on which the fan is to be 85 mounted. When the blades of the fan are to extend radially outward the strips will be bent to V form, the angles between the two blades of each strip depending upon the number of blades with which the fan is to 90 be provided. Adjacent blades of different strips are connected by means of strengthening pieces 26 preferably formed by metal sheets or webs as shown which are secured to the blades in any suitable manner as by 95 means of edge flanges 28 soldered or otherwise secured to the blades. By connecting the adjacent blades of different strips in this manner an extremely strong and rigid construction is secured without any connection whatever between the two blades *a* and *b* of each strip. The most rigid construction is secured by locating the strengthening pieces or webs intermediate the side edges of the blades, and to avoid any considerable 100 interference with the action of the fan the webs are preferably positioned as shown nearer the rear edge than the front edge of the blades. It is of advantage also to have the strengthening webs end short of the 105 110

outer ends or edges of the blades since this leaves the ends of the blades free to give or bend in the event of their striking any obstruction which may become jammed in the 5 fan casing, while at the same time the necessary rigidity of the blade is secured. If the unsupported end of a blade should become bent, it may be easily straightened out again, whereas if the strengthening webs 10 extended clear out to the ends of the blades an obstruction becoming caught within the fan casing might cause much greater damage.

The bent blade strips may be secured to 15 the hub in any suitable manner. A simple and strong way of securing them is shown in the drawing in which the V shaped bent strips are secured to the hub by screws, the intermediate or bent portions of the strips 20 being slightly flattened to afford space for the screw heads.

What is claimed is:

1. A rotary centrifugal fan comprising a hub, a plurality of blades extending outwardly from the hub and formed by strips 25 of sheet metal each bent to form two outwardly extending blades and having their intermediate or bent portions secured to the hub, and strengthening pieces connecting 30 adjacent blades of different strips.

2. A rotary centrifugal fan comprising a hub, a plurality of blades extending outwardly from the hub and formed of strips of sheet metal each bent to form two outwardly extending blades and having their intermediate or bent portions secured to the hub, and strengthening pieces connecting 35 adjacent blades of different strips, the space between adjacent blades of the same strip 40 being left clear.

3. A rotary centrifugal fan comprising a hub, a plurality of blades extending outwardly from the hub and formed by strips 45 of sheet metal each bent to form two outwardly extending blades and having their intermediate or bent portions secured to the hub, and strengthening webs connecting adjacent blades of different strips.

4. A rotary centrifugal fan comprising a 50 hub, a plurality of blades extending outwardly from the hub and formed by strips of sheet metal each bent to form two outwardly

extending blades and having their intermediate or bent portions secured to the hub, and strengthening webs connecting adjacent blades of different strips, said webs being located intermediate the side edges of the blades. 55

5. A rotary centrifugal fan comprising a hub, a plurality of radial blades formed by strips of sheet metal each bent to V shape to form two radial blades and having their intermediate or bent portions secured to the hub, and strengthening webs connecting adjacent blades of different strips, said 60 strengthening webs ending short of the outer ends of the blades.

6. A rotary centrifugal fan comprising a hub, and a plurality of radial blades formed of strips of sheet metal each bent to V shape 70 to form two radial blades and having their intermediate or bent portions secured to the hub, said blades being provided with strengthening means ending short of the outer ends of the blades.

7. A rotary fan comprising a hub, and a plurality of radial blades formed of strips of sheet metal each bent to V-shape to form two radial blades and having their intermediate or bent portions secured to the hub, 80 said blades being provided with strengthening means extending along the blades outward from a point adjacent the hub and ending short of the outer ends of the blades.

8. A rotary fan comprising a hub, and a 85 plurality of radial blades formed of strips of sheet metal each bent to V-shape to form two radial blades and having their intermediate or bent portions secured to the hub all in the same transverse plane, the intermediate portion of each strip being secured to the hub on the side thereof from which the blade portions of such strip extend, and said blades being provided with strengthening means extending along the blades outward from a point adjacent the hub. 90 95

In testimony whereof, I have hereunto set my hand in the presence of two subscribing witnesses.

WILLIAM W. ROSENFIELD.
